SLINGSHOT

William L. Walker, Athens, Ga.

Application May 28, 1946, Serial No. 672,816

1 Claim. (Cl. 124—20)

2

1 This invention relates to catapults and has more particular reference to devices popularly known as sling shots.

One object of the invention is to provide a sling shot in which the thumb and forefinger of the user's hand are used as the supporting means to which the ends of the resilient sling are attached.

Another object of the invention is to provide a sling shot having finger stalls attached to the free ends of the sling.

Another object of the invention is to provide a sling shot having improved means for securing the projectile-carrying element and the finger stalls to the elastic members.

A further object of the invention is to provide a sling shot which may readily be folded into a compact form for convenience in carrying in a pocket when not in use.

With the foregoing and other objects in view, the invention consists in the construction, combination and arrangement of parts hereinafter described and illustrated in the drawing, in which:

Fig. 1 is a perspective view of the preferred embodiment of the invention, showing the finger stalls mounted on the thumb and forefinger of the user's hand;

Fig. 2 is a perspective view of the sling shot shown in Fig. 1, showing the preferred method of using the sling shot;

Fig. 3 is a plan view of a blank used to make a thumb stall;

Fig. 4 is a plan view of a blank used to make a finger stall; and

Fig. 5 is a plan view of the projectile-carrying element.

There is shown in Fig. 1 a sling shot adapted to be used with the thumb and forefinger of the user's hand employed as the staff and comprising a pair of elastic members 10; a pocket or projectile-carrying element 11; a thumb stall 12; and a finger stall 13.

The elastic members 10 consist of elongated strips of elastic material and are preferably made of rubber or other similar material. The pocket or projectile-carrying element 11 consists of a flat, substantially rectangular strip of flexible material, preferably leather or other similar material and has its ends reduced in width to approximately the width of the elastic strips. The element 11 is securely fastened to one of the ends of each of the elastic members 10, preferably by vulcanization, as shown in Figs. 1 and 6.

In Figs. 3 and 4, there is shown the blank from

which the preferred form of the thumb and finger stalls are made. The thumb stall is formed from a flat, substantially rectangular strip 14 of flexible material, having an integral projection 15 formed centrally of its lower edge with the side edges 16 and 17 of the projection curving into the lower edge of the strip 14. The upper edge 18 of the strip 14 is made concave, all as clearly shown in Fig. 3. The completed thumb stall is formed by folding the strip 14 on its vertical median axis and suitably securing the overlapped edges together, thereby forming a flexible tubular member.

In use, the thumb stall is placed on the right or left thumb, with the projection 15 extending upwardly and the concave edge 18 snugly fitting the contour of the hand of the user, then the projection 15 is folded outwardly and downwardly into the position shown in Fig. 1.

20 The finger stall is formed with a flat, substantially rectangular strip 19 of flexible material having an integral projection 20 formed centrally of its lower edge, with the side edges 21 and 22 of the projection curving into the lower edge of the strip 19, as clearly shown in Fig. 4. The completed finger stall is formed by folding the strip 19 on its vertical median axis and suitably securing the overlapped edges together, thereby forming a flexible tubular member. In use, the finger stall is placed on the right or left forefinger with the projection 20 extending downwardly. The curvature of the side edges 21 and 22 of the projection 20 fitting the contour of the base of the user's forefinger, as shown in Fig. 1.

35 The thumb and forefinger stalls are preferably made of leather or other similar material and each of the projections 15 and 20 is securely fastened to one of the free ends of the elastic members 10, preferably by vulcanization.

40 The operation of the device is as follows:

The user places the thumb and finger stalls on the thumb and forefinger of either his right or left hand. The stalls should be well down on the thumb and finger, clear to the bases thereof, as shown in Fig. 1. A missile or projectile is then placed in the pocket element 11 and, with the free hand, the pocket element is pulled backwardly, stretching the elastic members 10. By letting go the pocket element suddenly, the missile is shot out of the pocket.

In the preferred method of using the sling shot, the hand carrying the thumb and finger stalls is clinched to form a fist, with the thumb projecting beyond the clinched fingers. Using

this method, there is no danger of an amateur hitting his hand when using the sling shot.

From the foregoing, it will be apparent that the present device provides a simple and practical construction which may be readily set up for use when desired, and may be folded into a compact form for convenience in carrying in a pocket when not in use.

What is claimed is:

A sling shot comprising a pair of elastic members; a flexible projectile carrying element having one of its ends secured to one end of one of the elastic members, and the other of its ends secured to one end of the other elastic member; a tubular open-ended forefinger stall having a tab at its lower end secured to the free end of one of said elastic members; and a tubular open-ended thumb stall having a tab at its upper end secured to the free end of the other of said elastic

members, the construction being such that when the forefinger and thumb of a user are placed in their respective stalls and the hand clinched to form a fist, a missile may be catapulted from the projectile carrying element without danger of hitting the user's hand.
